[57] CLAIM

The ornamental design for a carpet stretcher, as shown and described.

DESCRIPTION

FIG. 1 is a perspective view of a carpet stretcher showing my new design;

FIG. 2 is a front view thereof;

FIG. 3 is a left end view thereof;

FIG. 4 is a top view thereof;

FIG. 5 is a bottom view thereof;

FIG. 6 is a right end view thereof; and,

FIG. 7 is a back view thereof.

FIGS. 2-7 are shown on a larger scale, and in an alternate position for use, in comparison to FIG. 1.
